 corporation of New Jersey

Application August 2, 1940, Serial No. 349,850

10 Claims. (Cl. 101—40)

This invention relates to improvements in apparatus for printing upon hard, unyielding surfaces, such as the surfaces of glass containers and the like. The invention is particularly suited for printing upon small glass containers of the ampule type although it is applicable also to containers of larger size, such as bottles, jars and tubes of various sorts.

Certain problems are encountered in printing upon the surfaces of glass containers and the like due to irregularities and imperfections which destroy the true cylindrical character of the containers. This coupled with the hardness and unyielding nature of the surfaces makes it difficult to provide a clear and uniform printed impression upon the containers. Various schemes have been proposed heretofore for printing upon such containers but these have either been complicated, and therefore difficult and expensive to build and operate, or they have not been effective in providing clear-cut and uniform impressions upon the surfaces of the containers.

A primary object of the present invention has been to provide a simple and effective mechanism, easy to construct and operate, for printing clearly and uniformly upon various sorts of containers of the character mentioned. In dealing with small containers of the ampule type, the operation may be substantially continuous, i. e., the printing operation may be carried out while the container is shifted from one point to another by conveying means. When larger containers are being printed, it is preferable to impart a step-by-step movement to the conveying means so that the containers will be held temporarily at a printing station during the printing operation. Except for this possible intermittent operation of the conveying means, the apparatus may be said to operate continuously upon articles fed to it either automatically or by hand.

A special feature of the invention is the provision of means for retaining the containers on the conveying means at the printing station for free rotation and in such a manner as to avoid smearing of the printed matter applied to their surfaces. This is accomplished without lifting or otherwise shifting the axes of the containers.

Another feature is the provision of a relatively soft and yielding roller, formed of rubber or similar composition, for transferring the desired impression from suitable printing means to the surface of the article. In this way a uniform effect is produced upon the article in spite of surface irregularities which so frequently occur in connection with blown glass containers.

Still another feature of the invention is the provision of a suitable conveyor for automatically receiving the containers, after they have been printed, and supporting them in such a way as to avoid smearing of the ink forming the impression applied thereto. To insure the uniform drying of the containers, the conveyor is passed at a predetermined speed through a drying chamber which is maintained at a controlled temperature. Preferably the conveyor is adapted to be driven independently of the printing mechanism so as to avoid variation in the drying time due to interruptions in the operation of the printer. But at the same time it is necessary to drive the printer and conveyor in synchronism and maintain them in predetermined relation whenever the printer is in operation. Toward this end a common drive is employed for the printer and conveyor and a special clutch is provided for disabling the drive to the printer without disturbing the drive to the conveyor.

Fig. 1 is an elevational view of the improved printing mechanism and an associated conveyor and dryer.

Fig. 2 is a front elevation of the printing mechanism.

Fig. 3 is a rear elevation of the printer with the cover removed to show the gearing for operating the printing devices.

Fig. 15 is a transverse sectional view along the line 15—15 of Fig. 14.

Fig. 16 is a similar transverse sectional view along the line 16—16 of Fig. 14, looking in the opposite direction, as indicated by the arrows, and

Fig. 17 is a fragmentary detail showing in 15 transverse section a modified conveyor cup.

Referring now to the drawings, the illustrative apparatus includes a printing unit which is generally designated 16. This printing unit is mounted on a pedestal 17 which encloses the power means for operating the equipment, including, in addition to the printing unit, a conveyor chain 18. The arrows shown on the conveyor chain indicate the direction of movement of the various courses. The conveyor chain carries the printed containers to and through a drying chamber 19 in which the containers are subjected to a uniform and regulated drying temperature which may be maintained in any convenient way, as by the circulation of heated air or the like, preferably under the control of thermostatic devices, not shown. After traversing a series of loops or slings within the drying chamber, the conveyor chain passes outwardly at the opposite side of the chamber and then upwardly to a delivery table or unloading station 20. Here the printed and dried containers are automatically removed by dumping from the conveyor and may be suitably packed in cartons or the like by hand or by any appropriate automatic means. From the delivery table the conveyor chain travels into the drying chamber upwardly along the adjacent end wall, then across the top and then downwardly along the opposite end wall through which it is passed outwardly at a point near the bottom and returned to the printing unit through its supporting pedestal. The means for driving the conveying chain from within the pedestal will be hereinafter explained.

Printing unit

The printing unit is carried by a main frame comprising a vertically disposed web 21 having laterally extending flanges 22 and 23 around three sides and having similar flanges 24 of greater width at its base. A cover 24a, extending from the outer edge of flange 22 to the outer edge of flange 24, may be provided to enclose the driving mechanism, which will be later described. Near the bottom of the vertical web 21 is a hollow boss 25 forming a socket to receive a reduced hub portion 26 of a boss 27 at the lower end of an auxiliary frame member 28. This auxiliary frame is adapted to rock or pivot slightly by the turning of the hub portion 26 within the boss 25. Near its upper end the auxiliary frame 28 carries an integral sleeve 29 which extends through an aperture 30 in the web 21, this aperture being of sufficient size to permit a slight rocking or pivotal movement of the auxiliary frame, as explained. Above the sleeve 29 the auxiliary frame is formed with an ear 31 having an aperture 32, slightly elongated in a circumferential direction, to receive a locking bolt 33 having screw-threaded engagement with the web 21. The bolt 33 thus

provides means for clamping the auxiliary frame in any adjusted position permitted by the construction described. To effect the desired adjustment of the auxiliary frame, it is provided with a block 34, swivelled to the frame. A screw 35 (Fig. 3), threaded in the block 34 and held by a block 36 swivelled to the web 21, may be turned by the insertion of a screw-driver in its head 37 to shift the auxiliary frame about the axis of the hub 26 to the desired extent and the frame may then be clamped in its set position by the tightening of the bolt 33.

Within the sleeve 29 of the auxiliary frame there is journaled a shaft 38 (Fig. 4) to which is keyed, adjacent its righthand end, a carrier member 39 which serves to support and convey the ampules or other articles to be printed. A clamping collar 40 may be provided to retain the carrier upon the shaft. This construction is such that the carrier may be readily removed whenever it is desired to replace it by another carrier adapted for larger or smaller articles.

The carrier is essentially a relatively broad, disc-like member having a series of recesses or pockets 41 at spaced intervals in its periphery. Adjacent each of these recesses and on both faces of the carrier there is provided a pair of discs 42 freely rotatable upon studs 43 mounted in the carrier. These discs 42 are so arranged that their peripheries extend slightly beyond the surfaces defined by the recesses 41. Accordingly, these discs serve to support the ampules or other articles in such a way as to prevent contact of their surfaces with the surfaces defining the recesses 41. The outer periphery of the carrier is of generally cylindrical form, as indicated at 44, but in advance of each of the recesses 41 the outer surface of the carrier is inclined inwardly substantially toward the axis of the recess, as indicated at 45. This enables the carrier readily to pick up the articles, such as ampules X, which are delivered to the machine by means of a chute 46. As the lowermost ampule is picked up by one of the recesses 41, the next ampule will roll along the adjacent surface 44 of the carrier and then down the inclined portion 45 into the next recess which is brought opposite the chute. The chute 46 may be supplied with the articles to be printed in any suitable way, either by hand or by automatic means. It is supported by means of a bracket 47 having a split collar 48 at its lower end adapted to surround and be clamped upon the sleeve 29 of the auxiliary frame. The arrangement is preferably such that the chute 46 will be inclined slightly from front to rear (Fig. 5), i. e., downwardly toward the web 21, so as to cause the ampules to remain by gravity toward the rear of the chute.

As best shown in Fig. 6, a disc or plate 49 is provided between the carrier and the end of the sleeve 29, this disc being secured to the sleeve by means of a bracket 50. The disc in turn carries an angle bracket 51 arranged to support a guide 52 which extends over the top of the carrier. Adjacent the lower end of the chute the guide 52 is curled upwardly, as indicated at 53 (Fig. 5), and at its opposite end 54 the guide extends adjacent to the printing station, to be later described. Another guide 55 (Figs. 4, 5 and 6) is provided below the printing station, this guide having an opening or cut-away portion 56 in the region over which rolls the printed matter on the ampules. Preferably the connecting portions at the ends of the opening 56 are offset radially to a slight extent so as to lie outwardly of the

inner surface of the guide. It will be understood that the guide 55 serves to retain the ampules in the pockets 41 and for this reason, after the ampules have been printed upon, it is necessary to guard against smearing of the ink. The lower guide 55 is carried by a disc 57 secured to an arm or bracket 58 carried by a stationary shaft 59 extending through the hub 26 of the auxiliary frame and the boss 25 of the main frame. By shifting the bracket 58 axially of the shaft 59, 10 adjustment may be made for ampules of different length. A set-screw 60 may be provided at the bottom of the bracket 58 for retaining the latter in desired position on the shaft 59. At the top of the disc 57 a laterally extending support 61 is provided. This carries an adjustable bracket 62, which may be clamped in any adjusted position by a screw 63. The inner end of bracket 62 carries a flexible spring finger 64 adapted to engage the outer ends of the ampules to press them lightly 20 against the disc 49 as the ampules are carried into printing position. This insures the correct positioning of the ampules as they are being printed.

As the ampules with the printed impression thereon are carried beyond the lower end 65 of the guide 55, they are permitted to drop by gravity into a series of cups or baskets 66 carried by the conveyor chain 18, previously mentioned. These cups are freely supported by pins or rods 67 formed as extensions of the roller supporting pivots for the links of the conveyor chain. Just beneath the carrier 39 the conveyor passes around a sprocket wheel 68, loosely mounted upon the previously described shaft 59. A collar 69 serves to retain the sprocket in place. Each of the cups 66 is provided with a weighted bottom 70 which serves to maintain the cup in an upright position throughout its movement with the conveyor chain. To reduce to a minimum the sagging of the cups due to the cantilever effect, the weighted portion of the bottom may, if desired, be concentrated 40 near the chain, as shown at 70a in Fig. 17. At its rear or inner end each cup is provided with a trough 71 and at its outer end with a substantially vertical wall 72 having a shallow notch 73.

It will be understood that the conveyor chain is adapted to be driven in synchronism with the carrier 39, the arrangement being such that as an ampule is discharged from the carrier, one of the cups 66 will be directly beneath the latter to receive the ampule. Due to the construction of the cup, a portion of the long tip of the ampule will engage the depression 73 while the periphery of the bottom of the ampule will engage either the top of the pin 67 or the sloping walls of the trough portion 71 of the cup. As a result, none of the printed matter on the ampule will come in contact with any part of the cup and the danger of smearing the printed impression is eliminated.

The printing upon the ampules at the printing station is effected by means of a soft, resilient transfer roller 74. This may be formed of rubber or any other composition commonly employed in inking rolls. The entire roller may be formed of such material, if desired, although, preferably, only an outer band of appropriate thickness to provide the desired yield will be so formed. This transfer roller is carried by a shaft 75 and is held in place on the shaft by means of a circular nut 76 provided with spanner wrench openings. In the operation of the machine, the roller 74 will be driven at an appropriate speed in synchronism with the carrier 39, the construction illustrated being such that during a complete

revolution of the roller 74, two of the ampules will be presented at the printing station by the carrier. It has been found in this connection that in dealing with relatively small ampules, having a diameter of less than one-half inch, the carrier may be operated continuously and the printing operation thus performed while the ampule is being advanced by the carrier. The peripheral speed of the roller 74, as explained, will be considerably faster than that of the carrier so that the ampule at the printing station will be revolved upon the supporting discs 42 during the period of contact between the ampule and the roller. When larger ampules or containers having a diameter of more than half an inch are dealt with, it is preferable to operate the carrier intermittently so that it will be held stationary while the article presented at the printing station is receiving the printing impression.

The matter transferred to the ampule by the roller 74 is received by the latter from one or more printing or impression members designated generally at 77 in Fig. 2. In the drawings there is illustrated a pair of such printing members adapted for multi-color printing upon the ampules. Since both of the printing members and their associated inking devices are substantially the same, except for a slight difference in the arrangement of the parts, a description of one will suffice. It will be understood, however, that where two or more printing members are employed, they will be operated in synchronism and in such inter-relation as to insure proper registry of the different matters to be applied to the roller 74 and transferred to the ampules.

As best shown in Figs. 7, 8, 9 and 10, the printing member is carried by a shaft 78 and it comprises one or more discs 79 of partially cylindrical form. In the embodiment illustrated, two such discs are shown. This permits substitution of all, or only a part, of the matter to be printed. The matter to be printed by each disc is engraved or otherwise in intaglio in a band 80 having its ends turned inwardly for reception by grooves or notches 81 in a pair of retaining and adjusting cylinders 82. These cylinders are provided with square openings 83 for the reception of an appropriate wrench to effect the clamping and adjustment of the bands. A set-screw 84 is associated with each cylinder for holding it in any adjusted position. It will be seen that by turning and setting the cylinders 82, the band 80 may be held tightly against the disc 79 and its position circumferentially of the disc 79 may be adjusted to a certain extent, as may be required for proper registry.

The discs 79 are clamped tightly upon the shaft 78 by means of collars 85 and 86 forced against the opposite sides of the disc by means of nuts 87 and 88 provided with spanner wrench openings and adapted to cooperate with threaded portions of the shaft. It will be apparent that this arrangement for retaining the discs 79 enables their axial adjustment for proper registry purposes. A collar 89, integral with the shaft, is arranged to abut the end surface of a boss 90 formed on the supporting web 21. Spanner wrench openings in this collar will facilitate holding the shaft during adjustments. Within the boss 90 and surrounding the shaft 78 is an eccentric sleeve 91 having an extension at one end provided with an arm 92. A block 93 is swivelled on the arm and is connected by an adjustable screw 94 with another block 95 swivelled 70 on the frame 21. By proper adjustment of the

screw 94, the position of the eccentric sleeve may be varied to alter the position of the printing discs 79 in relation to the transfer roller 74. In this way the pressure between the transfer roller and printing discs may be varied to produce the desired effect.

Shaft 78 is adapted to be driven in synchronism with the transfer roller 74 but, in the construction illustrated, is driven at double the angular speed of the transfer roller. In this way two impressions are received and transferred by the roller 74 upon each revolution of the latter. The driving mechanism for accomplishing this will be subsequently described. For the purpose of driving the shaft 78, the latter is provided with a pinion 96 which is clamped in place against the sleeve 91 by means of a nut 97 arranged to be operated by a spanner wrench. On a reduced hub portion of the pinion 96, there is provided a braking device 98 which serves to eliminate the back lash in the teeth of the gearing by which the shaft is driven. This insures smoothness of operation and accuracy in the transfer of the printed matter to the ampules.

Any suitable means may be provided for supplying ink to the printing members for transference to the ampules. As best shown in Fig. 2, these means may include an ink font 99 pivotally supported at 100 on the main frame 21 and adjustable angularly by a set-screw 101. The ink from the font is supplied to the printing members by a series of rollers including a roller 102 at the end of the font, arranged to be operated by a ratchet mechanism 103 through a cam 104 secured to a shaft 105. This shaft is driven in synchronism with the other portions of the printing mechanism through connections to be later explained. Another cam 106, secured to the shaft 105, serves to rock an arm 107 pivotally mounted upon the frame at 108 and carrying at its outer end a roller 109. Cam 106 is arranged to rock the roller 109 into engagement with the roller 102 as the latter is being partially rotated by the ratchet mechanism through the cam 104. Upon the return of the roller 109 into engagement with a larger roller 110, mounted for rotation with the shaft 105, the ink delivered to the roller 109 will be transferred to the roller 110 and from the latter to the printing member by an intermediate inking roller 111. To insure the even distribution of the ink over the surface of the roller 110, a pair of spreader rollers 112 is provided at opposite sides, these being carried by spindles 113. Spindles 113, as well as the pivot 108 of the arm 107, are preferably shifted axially back and forth in the course of operation of the machine to further insure even distribution of the ink. For this purpose a large cam disc 114 (Figs. 2 and 4) is disposed at slightly less than a right angle to the shaft 105 to which it is secured. The pivot pin 108 and the spindles 113 are arranged to engage the inner face of the disc 114 and are urged against this face by spring-operated plungers 115. Accordingly, upon each revolution of the disc 114, the rollers 109 and 112 will be shifted back and forth a limited distance across the face of the roller 110.

Driving mechanism

For the purpose of driving the printing devices and the conveyor chain, a motor 116 may be provided within the pedestal portion 17 of the printer. (See Figs. 11 and 12. This motor may be connected by a belt 117 with a pulley 118 se-

cured to the input shaft of a speed reducer 119. The output shaft 120 (Fig. 11) of the speed reducer carries a sprocket 121 which is preferably loose on the shaft but adapted to be connected therewith through a clutch, to be later described. Sprocket 121 is connected by a chain 122 with a sprocket 123 carried by a shaft 124 mounted in the main frame 21. As best shown in Fig. 3, the shaft 124 carries a pinion 125 which meshes with a gear 126 secured to the shaft 75 of the transfer roller 74. Gear 126, in turn, meshes with the first of a train of gears 127 which carries the power to the printing member and inking devices. The first of these gears is secured to the shaft 78 which carries the printing members. In the illustrated construction the ratio of the gears is such that the shaft 78 will be given two revolutions for each revolution of the shaft 75. A train of gearing 128, similar to the gearing 127, serves to drive the other shaft 78 and the other inking devices. A pinion 129, secured to the shaft 75, meshes with a large gear 130 secured to the shaft 38 for driving the ampule carrier. In the illustrative mechanism, this gearing is such that the shaft 38 is revolved at one-third the angular speed of the shaft 75. A brake 131 (Fig. 4), similar to the brake 98, serves to apply an appropriate frictional resistance to the rotation of the shaft 38 so as to eliminate back lash in the gearing. An appropriate tension is maintained upon the driving chain 122 by means of an idler sprocket 132 carried by a spring-operated arm, as shown in Fig. 11.

Secured to the shaft 120 is another sprocket 133 connected by a chain 134 with a sprocket 135 secured to a shaft 136. A sprocket 137 secured to the shaft 136 is connected by a chain 138 with a sprocket 139 secured to a shaft 140. This series of chains and sprockets serves to drive the conveyor chain, the arrangement being such that the conveyor is driven so long as the motor 116 is in operation. Thus, even though the printer may be thrown out of operation, by the means to be later described, the articles carried by the conveyor through the drying chamber will continue their movement and will, therefore, be subjected to the same drying conditions. The speed reduction between the shaft 120 and the shaft 140, which drives the conveyor, is such that the cups 66 will be advanced at the same speed as the pockets 41 in the carrier. As best shown in Fig. 11, the conveyor chain 18, entering the pedestal 17 adjacent the lower end, is passed around a sprocket 141 secured to the shaft 140, and then around idlers 142 and 143, up to and around the sprocket 68, where the cups receive the printed ampules. The chain then passes downwardly to a sprocket 144, near the bottom of the pedestal, and outwardly to return to the drying chamber.

For the purpose of disconnecting the printer from the driving mechanism, whenever any difficulty is encountered in the printer or when the supply of ampules to be printed is exhausted, a clutch 145 (Fig. 12), is provided between the shaft 120 and the sprocket 121, as previously mentioned. This clutch is arranged to be operated by an arm 146 of a bell-crank whose other arm 147 is actuated through a link 148 connected with a hand-operated lever 149. By lifting or lowering the lever 149, the clutch may be engaged or disengaged, as desired. The clutch may be of any suitable construction but should be such as to insure proper synchronization of the printer with the conveyor whenever the clutch is engaged. As best shown in Fig. 13, it may

comprise a pin or key element 145a slideable in a passage in a hub member 121a of the sprocket 121. A spring 145b at the inner end of the passage urges the key element toward the left (Fig. 13) into engagement with a groove 145c in a hub member 133a which carries the sprocket 133 and is keyed for rotation with the shaft 120. The control arm 146 has a cam face 146a at its end adapted to cooperate with a cam face 145d forming one wall of a slot or notch cut in the side of pin 145a. This arrangement is such that the arm normally holds the pin 145a disengaged from the groove 145c so that the sprocket 121 will not be driven. However, when the arm 146, operating in an annular groove 121b in the hub 121a is withdrawn from the pin 145a by the operation of the lever 149, the spring 145b will urge the pin toward the hub 133a and will cause it to enter the groove 145c in the latter. Groove 145c is interrupted at one point by a stud 145e which engages and drives the key 145a and its sprocket when the key is in the groove. When it is desired to disengage the clutch, the arm 146 is shifted back to the Fig. 11 position in which the cam surface 146a is carried into the path of the surface 145d on the pin so that the latter is withdrawn from the groove 145c and the pin is carried by the momentum of the sprocket 121 into the position indicated in Fig. 13. As will be seen, the construction is such that the sprockets 121 and 133 will be connected for rotation in unison only when they are in a definite relation.

To facilitate the making of adjustments for the purpose of bringing about proper registry of the printed matter, a hand-wheel 150 is secured to the shaft 124 so that the various parts of the printer may be operated by hand during the adjusting operations. It will, of course, be desirable to disengage the clutch 145 at this time so that the conveyor chain and the driving connections from the motor need not be driven in the hand operation of the printer.

In Figs. 14, 15 and 16 a modified form of driving mechanism is illustrated, in which the carrier 39 is rotated intermittently rather than continuously. For this purpose an extra gear 151 is provided on the shaft 124, this being secured, as indicated in Fig. 15, to the sprocket 123. Gear 151 meshes with another gear 152 secured to a sleeve 153 surrounding an extension of the shaft 59. Sleeve 153 is provided with a radially extending Geneva driving arm 154 which carries a roller 155 arranged to cooperate with the slots of a Geneva wheel 156. The segment 157, also carried by the sleeve 153, provides the usual Geneva locking action in conjunction with the scalloped portions of the wheel 156. The ratio of the gearing is such that for each revolution of the shaft 124, the shaft 38 will be turned through 60°, thus presenting a new ampule or bottle to the printing station. The timing is such that the shifting of the carrier will take place while a blank or clean portion of the transfer wheel 74 is presented opposite the carrier. The remaining parts of the modified gearing, for the purpose of driving the transfer roller and the various inking devices, may be substantially the same as the corresponding parts of the gearing shown in Fig. 3.

Summary of operation

In the operation of the machine the ampules "X" will be supplied either by hand or automatically to the chute 46. Assuming that the motor has been set in operation, and the lever 149 has been shifted to the position in which the

clutch 145 is engaged, the roller 39 will be rotated at an appropriate speed of, say, 15 R. P. M. and as each of the pockets 41 passes the lower end of the chute, it will receive one of the ampules. A series of ampules will thus be fed, successively, to and through the printing position, in which they are engaged by the transfer roller 74 and receive the ink, constituting the matter to be printed, which has been previously applied to this roller by the printing member or members 77. In the primary embodiment illustrated, the peripheral speed of the transfer roller 74 will be three times that of the carrier and hence the ampules will be rotated upon their supporting discs 42, by the frictional driving action of the rolls, as they pass through the printing zone. If the modified construction of Figs. 14 to 16 is employed, the carrier 39 will, as explained, be shifted intermittently, while a blank or clean portion of the transfer wheel is presented toward the carrier, and the ampule will be held at the printing station during the period in which the ink is being transferred to it from the roller 74. The ampule will, of course, be rotated upon its supporting discs 42 in the course of this transfer.

After the ampules have been printed upon, they are still held in the recesses 41 by means of the guide 55, which is so cut away as to insure against smearing of the printed impression on the ampules. As the ampules reach the lower end 65 of the guide, they drop by gravity into the cups 66 of the endless conveyor and are carried to and through the drying chamber and to the delivery or packing station 20.

To insure proper pressure between the printing members 77 and the transfer roller 74, as well as between the latter and the ampules, appropriate adjustments should be made before the machine is set in operation. Thus, the screws 94 should be adjusted to shift the eccentric sleeves 91 to the positions best suited for the transfer of clear impressions from the printing members 79 to the roller 74. Proper registry of the printed matter, as between the two or more printing and inking units employed, may be effected by shifting the printing elements 80 circumferentially with respect to the discs 79 by appropriate rotation of the cylinders 82. The character of the impression transferred from the roller 74 to the ampules may be regulated by adjustment of the screw 35 which controls the shifting of the auxiliary frame 28. To facilitate the making of the various adjustments, the lever 149 is preferably shifted to disengage the clutch 145 and thus allow manual operation of the printing unit independently of the conveyor and the motor. The lever 149 may similarly be shifted to disconnect the printing unit whenever difficulty is encountered in its operation or when the supply of ampules in the chute 46 has been exhausted. The conveyor 18 will at such times continue its operation so as to complete the uniform drying of all of the ampules.

While an illustrative machine embodying the various features of the present invention and certain modifications have been disclosed in considerable detail, it will be understood that numerous other changes may be made in the construction and arrangement of the various parts without departing from the general principles and scope of the invention. The terms and expressions used herein have been used as terms of description and not of limitation.

What I claim is:

1. In an apparatus of the class described a rotatable carrier adapted to retain rotatable ar-

articles to be printed, said carrier having a fixed axis of rotation, means for driving said carrier continuously at a relatively low speed, means on said carrier for supporting a plurality of the articles for rotation about axes fixed relative to the carrier at a fixed radial distance from the axis of the carrier, a printing rotor having a fixed axis spaced from the axis of said carrier, and a continuously operating higher speed drive for said rotor, said rotor having a cylindrical yieldable printing surface, the continuous travel of the articles causing them to engage and indent the cylindrical yieldable printing surface during printing contact.

2. In apparatus of the class described an endless conveyor for printed articles, printing means for applying a printing impression to said articles, means for delivering the printed articles to said conveyor, common means for driving said printing and delivering means and said conveyor, and means operable at will for disconnecting said printing and delivering means from said driving means while said conveyor remains connected with said driving means and is driven thereby, said disconnecting means comprising a clutch so constructed and arranged that it will reconnect said printing and delivering means with said driving means in a particular relative position, thereby automatically bringing and maintaining said conveyor and said printing and delivering means in predetermined relation as they are driven.

3. In apparatus of the class described a rotatable article carrier, means for delivering articles to said carrier, means for rotating said carrier, means for printing upon the articles while on said carrier, conveying means arranged to receive articles from said carrier, common means for driving said carrier and conveying means in predetermined relation and for operating said printing means, and a clutch operable at will for disconnecting said printing means and said carrier from said driving means independently of said conveyor, said clutch being of the single revolution type and serving upon reconnection under manual control to automatically synchronize said printing means and carrier with said conveyor.

4. In apparatus of the class described a rotatable article carrier, means for delivering articles to said carrier, means for rotating said carrier, means for printing upon the articles while on said carrier, conveying means arranged to receive articles from said carrier, common means for driving said carrier and conveying means in predetermined relation and for operating said printing means, said conveying means being connected in definite relation to said common driving means, and a clutch for disconnecting said printing means and said carrier from said driving means independently of said conveying means, said clutch being constructed and arranged to connect said carrier with said driving means only in particular relation and when said carrier and conveying means are in predetermined relation.

5. In apparatus of the class described a rotatable article carrier, means for delivering articles to said carrier, means for rotating said carrier, means for printing upon the articles while on said carrier, conveying means arranged to receive articles from said carrier, common means for driving said carrier and conveying means in predetermined relation and for operating said printing means, a clutch for disconnecting said carrier from said driving means independently of said conveyor, the driving and driven members of said

clutch being engageable only when they are in a single, predetermined relative position, and means operable at will for controlling the engagement and disengagement of said clutch while the driving means is in operation.

6. In apparatus of the class described a rotatable carrier for articles of circular cross-section, means on said carrier for supporting said articles for free rotation relative to the carrier, a cylinder having a resilient yielding surface extending completely around the circumference thereof and arranged to engage said articles and rotate the same on said carrier, said cylinder simultaneously imparting an offset printing impression to said article, means for rotating the carrier to carry an article into and out of the path of said cylinder, and means for continuously driving said carrier and said cylinder.

7. In apparatus of the class described a rotatable carrier, said carrier having recesses in the periphery thereof for the reception of articles of circular cross section, a plurality of thin edged discs spaced circumferentially and axially of said carrier adjacent each of said recesses for engaging said articles at points spaced circumferentially and longitudinally thereof and supporting said articles free and clear of the walls of said recesses, means for rotating said carrier, means having a yielding resilient surface adapted to frictionally engage said articles and rotate the same on said discs as the articles are brought to a predetermined position by said carrier, and means associated with said last recited means enabling the latter to print upon said articles as they are rotated.

8. In apparatus of the class described a rotatable carrier, said carrier having recesses in the periphery thereof for the reception of articles of circular cross section, discs adjacent each of said recesses and disposed in predetermined relation thereto at opposite sides of the carrier for supporting said articles free and clear of the walls of said recesses, a support for said carrier angularly adjustable about a fixed pivot, means for angularly adjusting said support about said pivot and retaining the same in adjusted position, means for rotating said carrier, and impression means adapted to frictionally engage said articles and rotate the same on said discs as the articles are brought to a predetermined position by said carrier, the angular adjustment of said support being arranged to vary the frictional engagement between said means and articles.

9. In apparatus of the class described a rotatable carrier, said carrier having recesses in the periphery thereof for the reception of articles of circular cross section, discs adjacent and disposed in definite relation to each of said recesses at opposite sides of said carrier for supporting said articles free and clear of the walls of said recesses, means for rotating said carrier, means for supplying articles to the successive recesses by gravity as the carrier is rotated, a rockable frame for supporting said carrier and said article supplying means, a soft yieldable impression roller adjacent said carrier arranged to engage said articles and rotate the same on said discs, said roller being adapted to transfer printing impressions to said articles, printing means for applying printing impressions to said roller, said roller being mounted on a fixed shaft, and means for adjusting said carrier and printing means toward and from said roller, said adjusting means serving to rock said frame and thereby simultaneously adjusting said article supplying means.

10. In apparatus of the class described a rotatable carrier, pockets in the periphery thereof for articles of circular cross-section, discs mounted on said carrier at the opposite sides thereof for rotatably supporting the articles in each of said pockets in a predetermined position free and clear of the walls thereof, means for rotating said carrier simultaneously, an impression roller adjacent said carrier having an article engaging

5

surface extending completely around said roller and arranged to be frictionally engaged by articles on said carrier as the latter is rotated, and means for rotating said roller in synchronism with said carrier and thereby frictionally rotating the articles at the same surface speed while they are frictionally engaged by the roller.

JOHN H. FRIDÉN.
